A. KONOFF

DOLL'S EYES

Filed April 21, 1925

UNITED STATES PATENT OFFICE.

ALEXANDER KONOFF, OF NEW YORK, N. Y., ASSIGNOR TO OVERLAND METAL NOVELTY CO. INC., OF NEW YORK, N. Y., A CORPORATION OF NEW YORK.

DOLL'S EYES.

Application filed April 21, 1925. Serial No. 24,731.

To all whom it may concern:

Be it known that I, ALEXANDER KONOFF, a citizen of the United States, and resident of New York city, in the county and State of New York, have invented certain new and useful Improvements in Dolls' Eyes, of which the following is a specification.

This invention relates to an improvement in dolls' eyes, and particularly to the manner of constructing and mounting the eye balls upon their supporting rod.

An object of the invention is to provide an eye which is of simple and inexpensive construction and which may be easily connected with its supporting rod and which when so connected will be capable of universal rotary adjustment in order to properly accommodate itself to the eye socket in the doll's head.

20 A further and more detailed object is to provide an eye including an outer hemispherical shell, preferably of metal, and bearing the eye-picture on its outer surface, and a single attaching member connected

25 between the eye shell and its carrying rod constituting the sole element of connection between said shell and rod, and further to so connect the attaching member with the shell and rod that it will provide for both a

30 universal rotary adjustment of the shell with respect to the rod and a bodily adjustment of the eye along the length of the rod.

A still further detailed object is to so construct the parts that the eye shell will be capable of a desirably limited rotary movement upon the attaching member and about both horizontal and vertical axes transverse to the length of the supporting rod, and the attaching member being in turn rotatably adjustable upon the supporting rod.

40 A further object is to so construct the parts that they will be retained against likelihood of accidental displacement from any position into which they are manually adjusted.

45 Other objects and aims of the invention, more or less specific than those referred to above, will be in part obvious and in part pointed out in the course of the following description of the elements, combinations, arrangements of parts and applications of

principles, constituting the invention, and the scope of protection contemplated will be indicated in the appended claims.

55 In the accompanying drawings which are to be taken as a part of this specification, and in which I have shown merely a preferred form of embodiment of the invention:

60 Fig. 1 is a front elevational view of a portion of an eye set constructed in accordance with this invention.

65 Fig. 2 is a rear view of the eye appearing in Fig. 1.

70 Fig. 3 is a side elevational view of the eye seen in Fig. 2, the supporting rod being shown in transverse section.

Fig. 4 is a transverse vertical sectional view taken upon the plane of line IV-IV of Fig. 2.

75 Fig. 5 is a horizontal sectional view taken substantially upon the plane of line V-V of Fig. 2, the attaching member being shown in full lines.

Fig. 6 is a view similar to that seen in Fig. 5 but illustrating a modified construction of the attaching member.

Fig. 7 is a sectional view upon the plane of line VII-VII of Fig. 6, and

80 Fig. 8 is a rear view of the eye structure appearing in Figs. 6 and 7.

85 Referring to the drawings for describing in detail the structural parts shown therein the reference character L indicates the usual bracket member by means of which the eye set is intended to be connected with the inner surface of the forehead portion of a doll.

90 The reference character G indicates the cross, or supporting, rod which is rotatably mounted at the lower end of the bracket plate and which carries at its opposite ends the two eyes H-H.

95 The rod G has a pendant weight carrying arm 1 by which the eyes are gravity controlled in the usual manner.

The eyes are identical and a description of one will apply to both, as follows:

100 The hemispherical shell 2 has a notch 3 in one side thereof through which projects the supporting rod G.

The attaching member 4 is arranged at the rear of the shell 2 and consists of what will

be termed a main flat plate portion 5, a pair of spring arms 6—6 and a stem portion 7.

The main plate portion 5 extends vertically across the rear open side of the shell 2. 5 The spring arms 6—6 are formed at the upper and lower ends of this plate and curve forwardly in approximate conformity to the semispherical curvature of the interior surface of the shell. They are so made however that except for the presence of the shell they would spread apart, and thus they exert a continual friction pressure against the inner surface of the shell.

Suitable inturned flanges as 8—8 are provided at the rear edge of the shell in position to engage over the adjacent rear surface portions of the plate 5 for maintaining the spring arms in proper cooperative engagement with the shell at all times, and the 15 plate 5 at its opposite ends is punched upwardly to a suitable extent so as to provide aligned pivot portions 9 for direct engagement against the flanges 8 to thereby facilitate accurate pivotal adjustment of the eye shell with respect to the supporting rod, it being noted that the pivot points 9 are substantially in a common vertical plane with the center of the supporting rod in order that no appreciable bodily displacement of 20 the eye shell will accompany rotary adjustment of the eye shell when the shell is being fitted to its cooperative position within a doll's head, as will be readily understood by those skilled in the use of devices 25 of this kind.

In addition to adjustment of the eye shell about a vertical axis transverse to the length of the supporting rod, as just described, the structure also permits of a rotary adjustment 40 of the eye shell about a horizontal axis transverse to the supporting rod, that is that the shell may be easily rotated about such axis with the pivot points 9 meanwhile sliding along the under or forward surface of the flanges 8.

Both of these adjustments will be properly frictionally resisted by pressure of the spring arms 6 against the inner surface of the shell and by the resultant pressure of the 50 pivot parts or points 9 against the flanges 8, and this frictional resistance will be ample to maintain the shell in any position to which it is manually adjusted.

The stem portion 7 of the attaching member projects laterally from the main plate portion 5 and consists of a tubular sleeve adapted to telescope over the end of the supporting rod, the plate portion 5 being preferably formed with a groove as 10 therein so as to provide for unobstructed longitudinal movement of the sleeve along the supporting rod.

The stem or sleeve is formed from sheet metal bent into tubular shape but the edges 65 are preferably not fixedly connected together.

er, they may or may not have engagement with each other as suggested in my co-pending application Serial #K-1049. The sleeve is normally of less internal diameter than the external diameter of the supporting rod and must therefore be expanded when being forced onto the rod. Sufficient friction is thus generated to retain the sleeve in any position to which it is adjusted either longitudinally or rotatably upon the rod.

The several parts of the attaching member 4 may be separately formed and connected together if desired but they are preferably all formed as a stamping from a single piece of sheet metal as illustrated in 80 the drawings.

The opening 3 in the eye shell is sufficiently large to accommodate all necessary adjustments of the eye shell without any interference from the supporting rod, and it will be seen that by the structure described the eye shell is capable of manual rotary adjustment in all directions with respect to its supporting rod and about the spherical center of the eye shell, and that by reason of 90 the telescopic engagement of the stem portion 7 upon the supporting rod the eye may be readily adjusted as an entity longitudinally of the rod.

Referring now to the modification disclosed in Figs. 6, 7 and 8, it will be seen that the structure shown therein differs from the structure in the previous figures only as regards the construction of the attaching member. In Figs. 6, 7 and 8 the main plate as 11, corresponding to the plate 5, is somewhat larger than said plate 5 and is provided with additional spring arms 12—12, four such arms being illustrated. These arms curve forwardly and conform to and engage against the inner surface of the shell in the same manner and for the same purpose as do the arms 6 of the previous structure, and the plate 11 is provided with raised pivot portions or points 13 thereon for engaging the flanges 8 in the same manner as already described.

Oppositely pressed portions 14 and 15 of the plate 11 provide a socket directly upon said plate into which the end of the supporting rod G is inserted. The socket is normally slightly smaller than the diameter of the rod, and the parts forming the socket are suitably resilient so that when the rod is forced into the socket a sufficient amount of friction will be generated to retain the plate in any position of adjustment upon the rod to which it is moved either rotatably of the rod or longitudinally along the length of the rod.

As many changes could be made in this construction without departing from the scope of the invention as defined in the following claims, it is intended that all matter contained in the above description or shown

in the accompanying drawings, shall be interpreted as illustrative only and not in a limiting sense.

Having thus described my invention, what

5 I claim as new and desire to secure by Letters Patent is:—

1. An eye structure comprising a semi-spherical eye shell and an attaching member by which to connect said shell with the usual supporting rod, said attaching member comprising one portion to adjustably connect with the supporting rod and another portion providing spring fingers extending into the hollow of the eye shell and 15 having frictional engagement against the inner surface of said shell to thereby frictionally adjustably support the eye shell and means whereby said spring fingers are held in co-operative contact with said shell.

20 2. An eye structure comprising a semi-spherical eye shell and an attaching member by which to connect said shell with the usual supporting rod, and said attaching member comprising a plate extending across the rear open side of the eye shell, means provided by said plate to frictionally adjustably engage the supporting rod affording rotatable and longitudinal adjustment of the plate with respect to the rod, a plurality of 25 spring fingers formed upon said plate engaging the eye shell to frictionally adjustably support the eye shell, and means provided upon the eye shell and engaging portions of the plate to hold the spring fingers in co-operative engagement with the eye shell.

3. An eye structure comprising a semi-spherical eye shell and an attaching member by which to connect said shell with the usual supporting rod, and said attaching member comprising a plate extending across the rear open side of the eye shell, means provided by said plate to frictionally adjustably engage the supporting rod, said plate having 45 oppositely disposed extensions curved into conformity with the inner surface of the eye shell and constituting a pair of spring fingers engaging said inner surface of the eye shell to frictionally adjustably support the eye shell, and flanges provided upon the eye shell to retain the attaching member in co-operative position.

4. An eye structure comprising a semi-spherical eye shell and an attaching member by which to connect said shell with the usual supporting rod, and said attaching member comprising a plate extending across the rear open side of the eye shell, means provided by said plate to frictionally adjustably engage the supporting rod, and said plate having extensions at its opposite ends curved into conformity with the inner surface of the eye shell and constituting a pair of spring fingers engaging said inner surface of the eye shell to frictionally ad-

justably support the eye shell, together with flanges provided upon the eye shell and engaging said plate to retain the plate in co-operative position.

5. An eye structure comprising a semi-spherical eye shell and an attaching member by which to connect said shell with the usual supporting rod, the eye shell being open at its rear side and having diametrically disposed inturned flanges at its rear edge adapted to stand one vertically below and one vertically above the supporting rod, the attaching member comprising a plate extending across the rear open side of the eye shell having pivotal engagement with said flanges on a vertical axis, spring fingers provided upon said plate engaging the shell to hold the plate in pivotal engagement with the flanges and to frictionally resist the rotary adjustment of the shell on said vertical axis and also to provide rotary frictionally resisted adjustment of the shell with respect to the plate about a horizontal axis, together with means by which the plate is adapted for adjustable connection with the supporting rod.

6. An eye structure comprising a semi-spherical eye shell and an attaching member by which to connect said shell with the usual supporting rod, the eye shell being open at its rear side and having diametrically disposed inturned flanges at its rear edge adapted to stand one vertically below and one vertically above the supporting rod, the attaching member comprising a plate extending across the rear open side of the eye shell having pivotal engagement with said flanges on a vertical axis, spring fingers provided upon said plate engaging the shell to hold the plate in pivotal engagement with the flanges and to frictionally resist the rotary adjustment of the shell on said vertical axis and also to provide rotary frictionally resisted adjustment of the shell with respect to the plate about a horizontal axis, and said plate having oppositely disposed parts providing a spring socket by which it is adapted for adjustable connection with the supporting rod.

7. An eye structure comprising a semi-spherical eye shell and an attaching member by which to connect said shell with the usual supporting rod, the eye shell being open at its rear side and having diametrically disposed inturned flanges at its rear edge adapted to stand one vertically below and one vertically above the supporting rod, the attaching member comprising a plate extending across the rear open side of the eye shell having pivotal engagement with said flanges on a vertical axis, spring fingers provided upon said plate engaging the shell to hold the plate in pivotal engagement with the flanges and to frictionally resist the rotary adjustment of the shell on said vertical

axis and also to provide rotary frictionally resisted adjustment of the shell with respect to the plate about a horizontal axis, and said plate having integral parts thereof bent 5 to provide a spring socket by which it is adapted for adjustable connection with the supporting rod.

8. An eye structure comprising a shell, and an attaching member by which to connect said shell with the usual supporting rod, means by which the shell is pivotally connected with said attaching member, and said last mentioned means comprising a spring finger extension of the attaching member arranged to engage the shell to frictionally resist rotary movement of the shell with respect to the attaching member.

9. An eye structure comprising a shell, and an attaching member by which to connect said shell with the usual supporting rod, means by which the shell is pivotally connected with said attaching member, to afford rotary adjustment of the shell about axes at right angles to each other, and said 25 last mentioned means comprising a spring

finger extension of the attaching member arranged to engage the shell to frictionally resist rotary movement of the shell with respect to the attaching member, about both of said axes.

10. An eye structure comprising an eye shell having a spherical inner surface portion, an attaching member by which to adjustably connect said eye shell with the usual supporting rod, and said attaching member comprising a resiliently compressible part arranged within the eye shell and compressed by engagement with the spherical inner surface portion of said shell to thereby enable adjustment of the shell upon the attaching member and to frictionally resist and maintain such adjustment, the shell comprising means to retain said compressible part within the shell, and said attaching member also having another portion by which it may be connected with the supporting rod.

In testimony whereof I affix my signature.

ALEXANDER KONOFF.
